PILE-FABRIC LOOM

Application filed September 20, 1929. Serial No. 393,979.

This invention relates to pile fabric looms wherein the pile is formed by laying the pile forming strands over pile wires.

In some weaves employed in the production of pile fabrics two picks or weft threads are laid for each row of pile, while in other weaves three picks or weft threads are laid for each row of pile. When the former weave is employed a pile wire is inserted for every two picks whereas in the case of the latter weave a pile wire is inserted for every three picks.

In the weaves in which one pile wire is laid for every two picks the wire inserting and withdrawing mechanisms must be so actuated that they will insert and remove a pile wire while the loom is performing the cycles of operations involved in laying two picks, and in the weaves in which one pile is laid for each three picks the wire inserting and withdrawing mechanisms may operate at a slower speed since they may now utilize the period of time required to lay three picks in which to insert and withdraw a wire.

It will be seen from the above that the cycle of movements of a loom operated to insert a pile wire for every two picks is different from the cycle of movements in a loom operated to insert a wire for every three picks, and that the operating parts in the two looms must be differently synchronized.

It may be desirable in some cases to employ the same loom to weave either of the pile fabrics above mentioned, and the present invention therefore relates to a pile fabric loom which is so constructed that the synchronized operations of its different parts may be readily changed to cause the loom to insert a pile wire for every two picks under one adjustment and a pile wire for every three picks under a different adjustment.

If desired the speed of the crank shaft of the loom may be the same in a two shot as in a three shot operation, and if the speed of the crank shaft is not changed when the operation of the loom is altered to lay a different number of picks per pile wire, then the time available for inserting and removing a wire in a two shot operation is shorter than in a three shot operation. In the case of a broad

loom in which a long travel is required to insert and remove a pile wire, an appreciable period of time is required to perform the wire shifting operations. The interval of time which is required to complete the cycles of movement involved in laying two picks should therefore be carefully divided to permit the wire inserting and withdrawing operations to be performed in the available period of time without requiring any of the mechanism to be operated at an excessively high speed.

It is therefore found advisable in changing a loom from a three pick operation to a two pick operation or vice versa, to change the time for both inserting and withdrawing a wire, for if the time for either inserting a wire or withdrawing a wire is maintained the same in the two pick operation as in the three pick operation the small amount of time left is not sufficient for the proper performance of the remaining wire shifting operation.

An important feature of the present invention therefore resides in a pile fabric loom that is operable to lay one pile wire for every two picks under one adjustment and one pile wire for every three picks under a different adjustment, and in trains of mechanisms for operating different parts of the loom and provided with adjustable means for varying the synchronized operations of said different parts.

A more specific feature of the invention resides in a pile fabric loom having one train of mechanism for operating the shedding mechanism, another train of mechanism for operating the wire inserting mechanism and still another train of mechanism for operating the wire withdrawing mechanism, and in adjustable means included in each of said trains of mechanism and adapted to be adjusted to vary the synchronized operation of the parts driven by each of said trains.

A further feature of the present invention resides in clutch mechanism for operating the wire inserting scroll and in change speed means for varying the time for shifting the scroll operating clutch.

Still a further feature of the present invention resides in speed change mechanism for

varying the synchronized action of the shed forming mechanism and the jacquard mechanism with respect to the crank shaft.

The above and other features of the invention and novel combination of parts will be best understood from the following description when read in connection with the accompanying drawings illustrating one good practical form of the invention.

In the drawings:

Fig. 1 is a side elevation of a pile fabric loom with parts in section;

Fig. 2 is a front elevation of the wire controlling mechanism for the loom of Fig. 1;

Fig. 3 is a top plan view of driving mechanism containing the present invention and shown on an enlarged scale.

Fig. 4 is a sectional detail of the motor drive connection.

Fig. 5 is a detached detail showing parts of the driving mechanism.

Fig. 6 is an enlarged horizontal section showing details of the pile wire inserting mechanism.

Fig. 7 is a diagrammatic sectional view typifying an arrangement of the warp on the first shot of a two shot loom operation;

Fig. 8 is a similar view showing the arrangement of the warp on the second shot of a two shot loom operation;

Fig. 9 is a similar view showing the arrangement of the warp on the first shot of a three shot loom operation.

Fig. 10 shows the arrangement of the warp of Fig. 9 on the second shot; and

Fig. 11 shows the arrangement of the warp of Fig. 9 on the third shot.

The features of the present invention are illustrated in the drawings in connection with a broad pile fabric loom employing a scroll for inserting the pile wires and a chain for withdrawing the pile wires, but certain features of the present invention are applicable to looms employing other types of wire controlling mechanism.

The loom frame 1 may be of usual character, and mounted at the lower portion thereof is the lay rock shaft 2 carrying the lay swords 3 on which the lay 4 and reed 5 are mounted, Fig. 1, for cooperation with the shuttle 6 in laying and beating up the weft or filling as usual. A take-up roll 7 at the front of the loom driven by the worm wheel 8, serves to take-up the cloth as it is woven.

The beat-up movement may be imparted to the lay by any usual form of mechanism but in the present instance this movement is imparted to the lay by toggle levers 9 and 10 that are pivotally connected at 11 and the forward end of each lever 9 is pivotally connected to a bracket secured to the lay while the rear end of each lever 10 is pivotally secured to a fixed portion of the loom frame. The toggles 9 and 10 are operated by the crank shaft 12 having connecting links 13 between the toggle pivots

11 and the wrist pins of the crank shaft. The ground warp threads B¹, B² may be actuated by the harnesses 14 and the pile forming warp P may be controlled by the lingoies 15 actuated by jacquard mechanism, or otherwise.

The insertion and removal of the pile wires 16 is effected in the construction shown by a pile wire carriage or horse 17 that travels along a runway upon the supporting frame 18 and the carriage 17 is moved in the wire inserting direction by a rope or cable 19 that engages the operating scroll 20, and the carriage is moved in the wire withdrawing direction by the chain 21 driven by the large sprocket 22. The parts so far described may operate in a well known manner since the details thereof form no essential part of the present invention, but are shown and briefly mentioned to make clear the features of the invention to be hereinafter described.

In the construction shown the driving power for the loom is supplied by an electric motor 23 the shaft of which is provided with a pinion 24 that meshes with a gear 25 secured to a shaft 26. The shaft 26 is provided with a pinion 27 that drives the oppositely disposed gears 28 and 29 which may be of the same size. The gear 28 is secured to the crank shaft 12 and the gear 29 is secured to the shaft 30. Since, as above stated, it is unnecessary to change the speed of the crank shaft in changing from a two pick to a three pick operation or vice versa, the crank shaft may be given its desired constant speed from the motor as above described.

In the embodiment of the invention illustrated the sprocket 22 for operating the wire withdrawing chain 21 is mounted upon and driven by a shaft 31, and since it is desirable to change the speed of the chain 21 in changing the picks to be laid per pile wire the shaft 31 is provided with the change speed bevel gears 32 and 33 adapted to be selectively engaged with the bevel gears 34 and 35 respectively mounted upon the shaft 36. The gears 32 and 33 in the construction shown are rigidly secured to the shaft 31 while the gears 34 and 35 are keyed to the shaft 36 for sliding movement and may be held in the desired position lengthwise of the shaft by changing the position of the split spacing collars 37 and 38. It will be seen from the arrangement just described that when the gears 33 and 35 are engaged as shown in Fig. 3, the shaft 31 will be driven from the shaft 36 at one speed and when the gears 32 and 34 are engaged as shown in Fig. 5, the shaft 31 will be driven at a different speed. The shaft 36 is driven from the shaft 26 by the pinion 39 and gear 40.

In changing the loom from a two to a three-pick operation or vice versa, the timing of the operation of the harness mechanism and jacquard mechanism should be changed with respect to the crank shaft, and this is accom-

plished by providing the driving shaft 41 for operating the shedding mechanism. The speed at which the shaft 41 is driven may be varied by employing the change gears 42 and 43 upon the shaft 30 and the cooperating gears 44 and 45 upon the shaft 41. These gears may be constructed as shown in Fig. 4 wherein it will be seen that gear 42 is keyed to the shaft 30 while gear 45 is keyed to the shaft 41. The other two gears 43 and 44 are loosely mounted on their shafts but may be prevented from rotating upon the shafts upon which they are mounted by inserting the screws 46 to secure the gears together. It will therefore be seen that the shaft 41 may be driven at one speed from the shaft 30 through the gears 42, 44 and at a different speed through the gears 43, 45, depending upon the arrangement of the securing screws 46, and since the heddle mechanism and jacquard mechanism are operated from the shaft 41, their synchronized operation with respect to the crank shaft may be readily varied through the change gears just described.

In changing a loom so that it will lay a different number of picks per pile wire in accordance with the present invention the speed of the wire inserting mechanism is changed, a condition that is secured by changing the speed of the scroll operating shaft 47 and the timing of the mechanism for actuating the clutch 48 employed to drive the shaft 47.

In the scroll operating mechanism shown the clutch 48 for operatively connecting the aligned shafts 47, 49 may be a cone clutch of well known construction and is shown as having the outer cone element rigidly secured to the short shaft 49 while the inner cone element is keyed or otherwise secured to the shaft 47 for movement into and out of friction engagement with the outer cone element. The shaft 49 is driven by a bevel pinion 50 that engages a bevel gear 51 mounted upon the shaft 36. The arrangement is such that the gear 51 may be driven at one speed from the shaft 36 and at a different speed from the shaft 41. This is accomplished by the construction best shown in Fig. 6, wherein it will be seen that the bevel gear 51 is keyed to a sleeve 52 journaled upon the shaft 36 and that the sleeve has an integral or rigid pinion 53 that engages with a gear 54 upon the shaft 41. If the gear 51 is to be driven from the shaft 36 it is secured to the shoulder 55 which is keyed to the shaft 36 by inserting the bolts 56, and if the gear 51 is to be driven from the shaft 41 the bolts 56 are removed and the bolts 57 are inserted to secure the gear 54 to the shoulder 58 that is keyed to the shaft 41.

The operation of the scroll 20 to insert a pile wire is effected in the construction shown by providing the shaft 41 with a cam 59 adapted to engage an antifriction roller upon

the rocking lever 60 (see Fig. 1). The lever 60 is operatively connected to the clutch operating lever 61 by the link 62. The arrangement is such that the cooperating parts of the clutch 48 are normally retained out of engagement with each other by a spring (not shown) but the clutch is held closed to operate the scroll 20 during the short interval of time that the cam 59 holds the lever 60 in the position in which it is shown in Fig. 1.

When the operation of a loom is changed in accordance with the present invention to lay a different number of picks per pile wire it is also necessary to change the operation of the wire supporting switch 63 of well known construction with respect to the crank shaft movement in order to effect the proper insertion and withdrawal of the pile wires, but this may be accomplished by driving the switch operating cam (not shown) from the shaft 41.

When a pile fabric loom embodying the features of the present invention is adjusted to lay a pile wire for every two picks, the warps will occupy the position in which they are shown in Fig. 7 doing the first shot, so that the pile forming warps P will be laid over the inserted pile wire 16, while one set of ground warps B¹ will be partly raised and the other set of ground warps B² will be lowered to cause the first weft thread to be laid by the shuttle 6 between the warps B¹, B². On the second shot of the two shot loom operation the warps will occupy the position in which they are shown in Fig. 8 wherein it will be seen that the pile forming warps P and the ground warps B¹ are lowered while the ground warps B² are raised.

In case the loom is adjusted to lay one pile wire for every three picks the warps will occupy the position in which they are shown in Fig. 9 during the first shot, which arrangement it will be noted is the same as in Fig. 7. During the second shot of this three pick operation the warps will be positioned as shown in Fig. 10, with the ground warps B¹ raised and the ground warps B² and pile forming warps P lowered, and during the third shot of this three pick operation the warps will be positioned as shown in Fig. 11 wherein it will be seen that the warps B² are now raised while the warps B¹ are lowered.

In securing these changes in the operation of the loom, the action of the lay and of the shuttle picking mechanism may remain the same in laying either two shots or three shots per pile wire, and the change in the operation of the warp forming mechanism and wire controlling mechanism is secured by varying the operation of the driving mechanism above described.

It will be seen from the foregoing that in order to change from a two pick operation to a three pick operation or vice versa the

synchronized operations of a number of different parts of the loom require to be changed with respect to the speed of the crank shaft, and that the rate of change in speed required is different for different parts of the loom, 5 but that through the employment of the different trains of change speed mechanism shown and described the operation of the loom may be easily changed to insert a pile 10 wire for every two picks or every three picks as desired.

What is claimed is:—

1. In a pile fabric loom having means for weaving a ground fabric and for inserting and removing pile wires, in combination, 15 means for operating the loom to lay one pile wire for every two picks or one pile wire for every three picks depending upon the loom adjustment, including means for 20 operating the crank shaft at the same speed while laying one pile wire for every two picks or one pile wire for every three picks, different trains of change speed driving mechanisms, and manually adjustable means for 25 varying the operation of said trains of mechanisms relative to the crank shaft movement to thereby change the synchronized operations of the weaving and "pile wire" operating mechanism.
2. In a pile fabric loom having means for weaving a ground fabric and for inserting and removing pile wires, in combination, 30 means for operating the loom to lay one pile wire for every two picks or one pile wire for every three picks depending upon the loom adjustment, including means for operating the crank shaft at the same speed while laying one pile wire for every two picks or one pile wire for every three picks, a train 35 of change speed mechanism for operating the wire inserting and withdrawing mechanism, another train of change speed mechanism for operating the shed forming mechanism, and adjustable means for varying the operation 40 of said trains of mechanism relative to the crank shaft speed to thereby change the synchronized operations of the shed forming and the wire inserting and withdrawing mechanism.
3. In a pile fabric loom having means for weaving a ground fabric and for inserting and removing pile wires, in combination, 45 means for operating the looms to lay one pile wire for every two picks or one pile wire for every three picks depending upon the loom adjustment, including a train of mechanism for operating the wire inserting mechanism, a second train of mechanism for operating the wire withdrawing mechanism, a third 50 train of mechanism for operating the shed forming mechanism, and independently adjustable means in each of said trains of mechanisms for varying the synchronized operations of the parts driven thereby with respect to other going parts of the loom.

4. In a pile fabric loom having means for weaving a ground fabric and for inserting and removing pile wires, in combination, means for operating the loom to lay one pile wire for every two picks or one pile wire for 70 every three picks depending upon the loom adjustment, including means for operating the crank shaft at the same speed while laying one pile wire for every two picks or one pile wire for every three picks, different trains of driving mechanisms, and adjustable means for varying the operation speed of said trains of mechanisms to thereby change the synchronized operation of the shed forming mechanism and wire controlling mechanism with respect to the speed of the 75 crank shaft.

5. In a pile fabric loom having means for weaving a ground fabric and for inserting and removing pile wires, in combination, 80 means for operating the loom to lay one pile wire for every two picks or one pile wire for every three picks depending upon the loom adjustment, including different trains of mechanisms for operating the shed forming mechanism and the wire inserting and removing mechanism, and separate adjustable means in each of said trains of mechanisms for changing the synchronized operation of the mechanism driven by each of said trains 85 with respect to the lay crank shaft.

6. In a pile fabric loom having means for weaving a ground fabric and for inserting and removing pile wires, in combination, 90 means for operating the loom to lay one pile wire for every two picks or one pile wire for every three picks depending upon the loom adjustment, including shed shifting means and a driving train therefore, a wire inserting scroll and a driving train therefore, a wire withdrawing sprocket and a driving train therefore, and independently adjustable means in each of said trains for changing the synchronized operation of the parts actuated thereby with respect to the lay crank shaft. 95

7. In a pile fabric loom having means for weaving a ground fabric and for inserting and removing pile wires, in combination, 100 means for operating the loom to lay one pile wire for every two picks or one pile wire for every three picks depending upon the loom adjustment, including different trains of driving mechanisms, and adjustable means in each of said trains and adapted when moved to one position to operate the parts driven thereby in one predetermined synchronized relation to the lay crank shaft and when moved to a second position to operate the parts driven by each of said trains at a different predetermined synchronized relation to the lay crank shaft. 105

8. In a pile fabric loom having means for weaving a ground fabric and for inserting and removing pile wires, in combination, 115 means for operating the loom to lay one 120 different predetermined synchronized relation to the lay crank shaft.

pile wire for every two picks or one pile wire for every three picks depending upon the loom adjustment, including one train of mechanism for operating the shed forming mechanism and another train of mechanism including a clutch for operating the wire inserting mechanism, adjustable means in each of said trains of mechanism for changing the synchronized operation of the parts driven thereby with respect to the lay crank shaft, and means operable from said first train of mechanism for shifting said clutch to actuate the wire inserting mechanism.

9. In a pile fabric loom having means for weaving a ground fabric and for inserting and removing pile wires, in combination, means for operating the loom to lay one pile wire for every two picks or one pile wire for every three picks depending upon the loom adjustment, including one train of mechanism for operating the shed forming mechanism, a second train of mechanism for operating the wire inserting mechanism, a third train of mechanism for operating the wire withdrawing mechanism, separate, manually-adjustable, change speed means in each of said trains of mechanisms and adapted to operate the parts driven by each train at either one of two different predetermined speeds relative to the lay crank shaft.

In testimony whereof, I have signed my name to this specification.

EDWIN W. STONE.
